UNITED STATES PATENT OFFICE.

ALFRED M. ZIEGLER, OF BOSTON, MASSACHUSETTS, ASSIGNOR TO A. ZIEGLER & SONS CO., OF ROXBURY, MASSACHUSETTS, A CORPORATION OF MASSACHUSETTS.

DESIGN FOR A WAIST-BELT.

45,580.

Specification for Design.

Patented Apr. 7, 1914.

Application filed November 13, 1911. Serial No. 660,148. Term of patent 14 years.

To all whom it may concern:

Be it known that I, ALFRED M. ZIEGLER, a citizen of the United States, and resident of Boston, county of Suffolk, State of Massachusetts, have invented a new, ornamental, and original Design for Waist-Belts, of which the following is a specification, reference being had to the accompanying drawing, forming part thereof, the design consisting in the end or tip part of the belt, whereon is shown a U-shaped raised portion in the nature of embroidery, said U-shaped raised portion situated a slight distance from the edge of the belt and parallel thereto.

The drawing is a perspective view of a waist belt having a tip showing my new design.

I claim:

The ornamental design for a waist belt as shown and described.

ALFRED M. ZIEGLER.
